[57] CLAIM

The ornamental design for a tire, as shown and described.

DESCRIPTION

FIG. 1 is a perspective view of a tire showing one embodiment of our new design, it being understood that the tread pattern is repeated throughout the circumference of the tire, the opposite side being substantially the same as that shown;

FIG. 2 is a front elevation view thereof;

FIG. 3 is a side elevation view thereof on a reduced scale; and

FIG. 4 is an enlarged, fragmentary front elevation view thereof.

FIG. I

FIG.2

FIG.3
